E.W. Bond

Attorney.

UNITED STATES PATENT OFFICE.

JOHN MELUS GUYNN, OF NEWPORT, ARKANSAS, ASSIGNOR OF ONE-HALF TO JOHN DAVID McLAIN, OF NEWPORT, ARKANSAS.

DUMPING WAGON.

Application filed March 13, 1922. Serial No. 543,504.

To all whom it may concern:

Be it known that I, JOHN M. GUYNN, a citizen of the United States, residing at Newport, in the county of Jackson and State 5 of Arkansas, have invented certain new and useful Improvements in Dumping Wagons, of which the following is a specification.

This invention relates to certain new and useful improvements in dumping wagons 10 and more particularly to the bed thereof.

The present invention has for its objects among others to provide a simple and cheap dumping wagon in which the bed can be readily changed and which can be made 15 suitable for any road wagon, from a one-horse wagon to any of the larger varieties. It can be easily and quickly taken off or put on the same as any other form of wagon bed, and is in effect three beds in one and 20 yet costs practically no more than one. Suitable means are provided for holding the bed in operative position against tilting and yet the scoop can be readily allowed to tilt when desired, or it can be as 25 easily allowed to drop from the wagon when occasion may require.

Other objects and advantages of the invention will hereinafter appear and the novel features thereof will be particularly 30 defined by the appended claims.

The invention is clearly illustrated in the accompanying drawings, which, with the numerals of reference marked thereon, form 35 a part of this specification, and in which—

Figure 1 is a side elevation of my improved dumping wagon.

Figure 2 is a top plan thereof.

Figure 3 is a vertical longitudinal section thereof, as on the line 3—3 of Figure 2.

Figure 4 is a vertical cross section, as on the line 4—4 of Figure 3, looking in the direction of the arrows.

Figure 5 is a perspective view of the device for locking the front end of the scoop against tilting.

Like numerals of reference indicate like parts throughout the several views.

Referring to the drawings,

1 designates the rear axle, 2 the rear wheels and 3 the rear bolster. 4 is the front axle, 5 the front wheels and 6 the front bolster. 7 is the pole or tongue and 8, 8 the sides of the body which are adapted to

be supported upon the transverse members 55 9 and braced by means of suitable braces 10 secured to the ends of said transverse members and to said sides 8 by bolts or any suitable means.

11 and 12 are additional cross bars at the 60 front, while 13 and 14 are other cross bars at the rear between which the bolsters are disposed, as seen clearly in Figure 3.

The sides at the rear are connected and braced by means of a transverse rod 15 provided upon one end with a nut 16 whereby the same may be tightened when desired, and the said sides 8 at the rear are cut-away upon an incline, as seen at 17, forming inclined rests for the transverse board 70 18 secured to the under side of the rear scoop board 19, the ends of said transverse board being extended, as seen at 20, to engage the shoulders 21 on the sides 8 at the rearward terminals of the inclines 17. 75

The scoop board 19 at its forward end upon its under side is provided with a transverse cleat 22, as seen best in Figure 3, the rear edge of which is adapted to engage the forward edge of the transverse member 9, and upon the under face of the said scoop member 19 is a transverse strip 23 of less dimensions than the transverse member 22, and secured adjacent thereto to bear upon the upper face of the adjacent transverse member 9, as seen in Figure 3. This gives a rigid support for the scoop member 19 and prevents movement thereof to the front or rear but permitting of ready removal of the scoop member when desired. 90 It will be readily understood from Figures 1 and 3 that when in position the scoop member 19 is inclined downwardly and forwardly.

24 is a foot-rest supported from the transverse front board 25, being braced by suitable braces or the like 26. This member 24 may constitute a seat, if desired, or the driver may utilize the transverse board 27 secured to the front of the dumping member 28, as a seat, if desired. 95

This dumping member 28 is formed of a bottom 29, and the sides 30, the upper rear edges of which may be inclined rearwardly, as seen at 31 in Figure 3. As seen clearly 105 in Figure 3, the front transverse member 27 is extended, as at 32, beyond the front board 33 of the dumping member 28, and

this extension is designed to rest upon the top edge of the front board 34 which connects the front ends of the sides 8, all as clearly seen in Figure 3.

5 The dumping member 28 is pivotally mounted between its ends so as to be easily dumped. In the present instance I have chosen to show the pivotal support of this member as consisting of yokes or the like 10 35 which are pivotally suspended upon transverse rods 36 or the like, which extend lengthwise of the sides 8 and are mounted in suitable brackets or the like 37 secured by bolts or the like 38 to the sides of the body. 15 These yokes or the like are designed to be swung downward upon their pivots from the dotted line position seen in Figure 4 to the full line position shown in said figure and to engage the round portions 39 20 formed on the opposite ends of the transverse member 40 which is secured to the under side of the bottom 29 of the dumping member, as will be readily understood upon reference to Figure 4.

25 In order to hold the front end of the member 28 down I provide a rocking member 41 suitably held on the front board 25, as seen best in Figure 2, being mounted to revolve for the requisite distance by being retained within the keepers or staples 42, and having near its center the handle portion 43 by which it may be manipulated when desired. The member 41 is provided with the right angled portions 44 at the ends 35 to extend substantially parallel with the sides of the body and member 28 and also with the arms 45 at right angles to the members 44, as seen clearly in Figures 2 and 5, to extend inward across the tops of the sides 40 8 and the sides of the member 28, as seen in Figure 2, and the ends are then given the downward terminals 46, as seen in Figures 3 and 5, which engage the inner walls of the sides of the member 28 45 and hold the said member securely to its lowered or horizontal position. When it is desired to tilt the member 28, the handle portion 43 is moved downward to the front, which clears the members 45 and 46 from 50 their engagement with the sides of the body and member 28 and the latter is free to be dumped or inclined or tilted on its fulcrum.

The rear reach 47 is detachably held in position in the following manner: its rear end 55 is slidably held between the upper and lower rear bolsters, as seen in Figure 3, its forward end being slidably held in the hanger or loop 48 depending from the cross bar 9, the said reach passing between the braces 60 49 and 50, secured at their rear ends to the rear axle, and held against undue movement lengthwise by a bolt or the like 51 passed vertically through the reach and the braces. Removal of this bolt permits of the re- 65 moval of the rear bolster and rear axle, the

reach being moved endwise until it is out of engagement in the loop 48, as will be readily understood. It will be seen that the rear bolster is fitted between the rear cross bars 13 and 14, as shown in Figure 3. 70

The front bolster is likewise held between the front cross bars 11 and 12, as seen in Figure 3, the king pin 52 being passed through the said front bolster and axle and also through the front reach 53 to which 75 the pole 7 is pivoted, as at 54, the rear end of the said front reach being loosely retained within the loop or hanger 55 depending from the cross bar 9, as seen best in Figure 3. By removal of the king pin, the front axle 80 and bolsters and the front wheels and pole may be easily removed when desired.

The operation will be readily understood. Normally the parts are in the position shown in Figures 1 and 2 and full lines in Figure 85 3. When it is desired to dump the load that is within the member 28, the locking member 41 at the front is disengaged from the sides of the body and of the member 28, and then by simply swinging the member 28 upon its 90 fulcrums 35—39 the said member will be caused to assume the inclined position seen by dotted lines in Figure 3. It may be turned to any desired inclination, and when it is desired to remove the said member 28 95 entirely from the wagon body all that it is necessary to do is to disengage the loops 35 from the trunnions 39 on the cross bar 40 and the said member 28 can be dropped downward from the body and used upon 100 another body or replaced by another. As seen in Figure 2, the cross member 27 is of such width as to allow of the member 28 readily dropping between the sides 8 of the body when desired. 105

Modifications in detail may be resorted to without departing from the spirit of the invention or sacrificing any of its advantages.

What is claimed as new is:—

1. In a dumping wagon, a tiltable bed, detachably supported for bodily removal downward, suspension means therefor detachably connected with said bed, and means for fastening the front end of said bed 110 against pivotal movement.

2. In a dumping wagon, opposed rear and front members removably supported within the wagon body with their adjacent ends abutting and pivoted suspension means for 115 pivotally mounting one of said members, the front member being bodily movable downward for bodily removal, and means normally preventing such movement.

3. In a dumping wagon, a removable bed 120 of two abutting sections, pivotal suspension means detachably connected with one of said members whereby it is detachably pivotally mounted, and means for securing the front 125 end of the front section against movement, 130

the front member being bodily movable downward for bodily removal, and means normally preventing such movement.

4. In a dumping wagon, a tilting bed, and swinging yokes in which the same is fulcrumed and transverse rods extended upon the sides, said yokes being movable outward to disengage said rods.

5. In a dumping wagon, a tilttable bed, 10 having a cross bar with trunnions, and swinging yokes having portions to detachably receive said trunnions.

6. In a dumping wagon, a pivoted bed section, pivotally suspended supporting 15 means therefor, means for releasing the pivots thereof, and means engageable over the sides of said bed for locking the front end thereof against movement, said section being mounted for bodily removal by

dropping downward only, and means for 20 normally preventing such movement.

7. In a dumping wagon, a removable bed, means for detachably pivoting the same, and a rotatable member at the front end of the wagon body having portions to engage 25 over opposite sides of said body and the sides of the bed to lock the latter against movement.

8. In a dumping wagon, the body, a bed pivoted therein, and a rotatable member at 30 the front of the body having portions extended rearward, with portions extended laterally over the tops of the sides of the body and bed, and downwardly extended portions to engage the inner faces of the 35 sides of the bed.

In testimony whereof I affix my signature.
JOHN MELUS GUYNNE.
